UNITED STATES PATENT OFFICE.

ANDREW MYER TAYLOR, OF PORT EWEN, NEW YORK.

PORTABLE GARMENT-HANGER.

No. 802,245.

Specification of Letters Patent.

Patented Oct. 17, 1905.

Application filed February 17, 1905. Serial No. 246,080.

To all whom it may concern:

Be it known that I, ANDREW MYER TAYLOR, a citizen of the United States, and a resident of Port Ewen, in the county of Ulster 5 and State of New York, have invented a new and Improved Portable Garment-Hanger, of which the following is a full, clear, and exact description.

The object of the invention is to provide a 10 new and improved portable garment-hanger which is simple and durable in construction, cheap to manufacture, readily set up for use and easily folded for convenient storing in a traveling-bag, valise, and the like, and arranged to conveniently support a number of 15 articles, such as a coat, vest, overcoat, trousers, and hat.

The invention consists of novel features and parts and combinations of the same, as 20 will be more fully described hereinafter and then pointed out in the claims.

A practical embodiment of the invention is represented in the accompanying drawings, forming a part of this specification, in 25 which similar characters of reference indicate corresponding parts in both views.

Figure 1 is a perspective view of the improvement set up ready for use, and Fig. 2 is a side elevation of the upper portion of the 30 improvement as suspended from the top of a door.

The improved portable garment-hanger is preferably made of wire, one piece of which is formed into a back A, on the upper end of 35 which is pivoted at B' a supporting-rod B, provided at one end with a ring B² to permit of conveniently hanging the portable garment-hanger onto a nail or other similar support, the said rod B in this case being fastened to the back A by a ring C engaging the 40 rear end B³ of the rod B, as plainly indicated in dotted lines in Fig. 2. When the rod B is in this position, it practically forms an extension of the upper end of the back A, but 45 when a nail or similar support is not available then the rod B is swung into an angular position relative to the back A, as plainly shown in Figs. 1 and 2, so that the rear end B³ of the rod can be engaged with the top of 50 a door D or similar support to suspend the garment-hanger from the said door. It is understood that the rod B can swing from a vertical position into this angular position; but further swinging motion of the rod is 55 prevented by a suitable stop B⁴ between the rod and the back A.

The back A is provided between its ends with eyes A' and A², located one above the other and on which are fulcrumed supporting-bars E and F, each provided at its outer 60 end with loops to form a wide support for the garment to be supported. A distance below the lowermost eye A² is arranged a forwardly-extending coat - hook G for supporting a heavy garment, such as an overcoat, while a 65 coat is preferably hung on the supporting-bar E and a vest on the supporting-bar F.

The lower end of the back A terminates in a small hook A³, adapted to be engaged by the eye H' of a trousers-support H of any approved construction, the said trousers-support being arranged to clamp the trousers in 70 position, so that the trousers hang naturally down from the said support to avoid folding and consequent creasing of the trousers. 75

When the device is not in use, the supports E and F can be readily swung on the eyes A' and A² into alignment with the back A, so as to take up very little room, and the trousers-support H when the device is not to be used 80 is disengaged from the small hook A³ and placed lengthwise on the back A, so that the entire garment-hanger takes up very little room to permit its convenient storing in a small satchel, valise, or the like. 85

When the rod B is suspended from the door D as described, the front or looped portion B² of the said rod can be used as a support for a hat or like article.

The trousers-support H is preferably made 90 of a single piece of wire bent to form the longitudinal members H² H³ H⁴, of which the middle or clamping member H³ is mounted to turn on the connecting end member H⁵ as a pivot, the said end member H⁵ connecting 95 the top and bottom members H² and H⁴ with each other at one end. The free end of the clamping member H³ is adapted to engage a spring-clamp H⁶, formed by the other connecting member for the top and bottom 100 members H² H⁴. By the arrangement described the clamping member H³ can be readily opened to permit of placing the waistband of the trousers in position and between the members H² H⁴. When this is done, the 105 clamping member H³ is closed to hold the garment in place.

From the foregoing it will be seen that the device is very simple and durable in construction, can be cheaply manufactured of 110 single pieces of wire united in the manner described, and the device can be quickly set

up and suspended from a suitable support in a room as described.

Having thus described my invention, I claim as new and desire to secure by Letters 5 Patent—

1. A portable garment-hanger comprising a back provided between its ends with eyes, a small hook at the lower end of the back, a coat-hook integral with the back, above the 10 small hook, and a supporting-rod pivoted at the upper end of the back, the supporting-rod being adapted to suspend the hanger from a fixed support and to support a hat or like article.

15 2. A portable garment-hanger comprising a back provided between its ends with eyes, a small hook at the lower end of the back, a coat-hook integral with the back, above the small hook, a supporting-rod pivoted at the 20 upper end of the back, the supporting-rod being adapted to suspend the hanger from a fixed support and to support a hat or like article, and supporting-bars hung at their middles in the said eyes, to stand at right 25 angles to the back or fold lengthwise thereof.

3. A portable garment-hanger comprising a back provided between its ends with eyes, a small hook at the lower end of the back, a coat-hook integral with the back, above the 30 small hook, a supporting-rod pivoted at the upper end of the back, the supporting-rod being adapted to suspend the hanger from a fixed support and to support a hat or like ar-

35 ticle, supporting-bars hung at their middles in the said eyes, to stand at right angles to the back or fold lengthwise thereof, and a trousers-support adapted to be hung at its middle to the said small hook.

4. A portable garment-hanger provided with a back, garment-supporting devices 40 hung on the said back, one above the other, a coat-hook on the said back, below the said devices, and a supporting-rod fulcrumed on the upper end of the back and adapted to swing at an angle thereto, to suspend the 45 garment-hanger from a fixed support and to support an article of wearing-apparel.

5. A portable garment-hanger provided with a back, garment-supporting devices hung on the said back, one above the other, 50 a coat-hook on the said back, below the said devices, a supporting-rod fulcrumed on the upper end of the back and adapted to swing at an angle thereto, to suspend the garment-hanger from a fixed support and to support 55 an article of wearing-apparel, and means for locking the supporting-rod in position on the said back.

In testimony whereof I have signed my name to this specification in the presence of 60 two subscribing witnesses.

ANDREW MYER TAYLOR.
